UNITED STATES PATENT OFFICE.

ARTHUR WOODROFFE MANTON, OF WANSTEAD, ENGLAND.

APPARATUS FOR BORING TUNNELS.

SPECIFICATION forming part of Letters Patent No. 673,717, dated May 7, 1901.

Application filed December 10, 1900. Serial No. 39,398. (No model.)

To all whom it may concern:

Be it known that I, ARTHUR WOODROFFE MANTON, a subject of the Queen of Great Britain, residing at Tudor Lodge, Sylvan road, 5 Wanstead, county of Essex, England, have invented new and useful Improvements in Apparatus for Boring Tunnels or Headings, of which the following is a specification.

This invention relates to improvements in 10 apparatus for boring tunnels or headings of the kind wherein revolving cutters are employed, the said cutters being gradually advanced automatically as the work proceeds, and has for its object to provide means where- 15 by tunnels or headings can be excavated and the excavated material removed from the tunnel or heading with greater facility and more quickly than heretofore, thereby effecting considerable economy in time and expense in 20 carrying out this description of work.

According to my invention I mount the cutters, which may be in the shape of cutting-knives or of cutting-disks free to rotate, upon a face-plate secured to a rotating cylinder, 25 horizontally or otherwise arranged, the said cylinder being loosely mounted upon a ring or bearing which is suitably fixed to a tunneling-shield of ordinary construction or to the tunnel or heading itself by means of sup- 30 ports or abutments. To reduce friction, rollers are provided between the fast ring or bearing and the cutting-cylinder, which is rotated thereon by any suitable means, such means advantageously consisting of a pulley-ring 35 sliding longitudinally upon the cutter-cylinder as the latter is advanced and brought back and adapted to be driven by a chain, rope, or belt from any separate and suitable source of power, preferably an electric, com- 40 pressed-air, or hydraulic motor—as, for instance, the advance pumping-motor if a shield be used. To advance the cutters automatically, I form upon the inside of the rotating cutting-cylinder an annular nut, which gears 45 with an external screw-thread upon the fast ring or bearing upon which the cylinder rotates. The cutters are brought back when the shield, if one be used, is to be driven forward or for the advancement of the apparatus in the 50 same way, but preferably at a greater speed to economize time.

Suitable means, such as a screw or screws,

are provided for withdrawing the apparatus for repairs or renewals or for varying the amount of advance of the apparatus as the 55 work proceeds.

The cutters may be so arranged upon the face-plate that they cut away the whole or the central portion of the surface of the tunnel or heading to be excavated, or they may 60 be arranged so as to leave a central uncut core, which passes through a hole in the said face-plate and through the fixed ring or bearing and can be removed in any suitable manner.

Suitable fixed or rotating vanes are pro- 65 vided for collecting the excavations, remov- 70 ing the same from the excavated surfaces, and delivering them or the greater portion thereof onto the working platform of the shield, tunnel, or heading.

In the accompanying drawings, Figure 1 is 75 a longitudinal sectional elevation of boring apparatus constructed according to the in- 80 vention and shown in conjunction with a shield. Fig. 2 is a half rear view of the ap- 85 paratus shown in conjunction with a shield. Fig. 3 is a half front view of the apparatus. Fig. 4 is a transverse section of a tunnel, showing the driving-gear for the boring ap- 90 paratus in end elevation; and Fig. 5 is a lon- 95 gitudinal section of a portion of a tunnel, showing the driving-gear in side elevation. Fig. 6 is a sectional elevation of boring ap- 100 paratus used without a shield and shown in position in a tunnel. Fig. 7 is a rear view of a part thereof.

A is the clay or stratum through which the tunnel is to be bored, and B is the completed portion of the tunnel.

C is the shield in the arrangement shown 90 in Figs. 1 to 5.

a are the cutters, the said cutters being shown in the form of cutting-knives and ar- 95 ranged upon radial arms b b, forming the face-plate, the said arms, however, not ex- 100 tends wholly from the periphery to the center, but being of such a length that when the apparatus is in operation an annular portion only of the clay is cut away, thus leaving a central uncut core D of material, as herein- after described.

c is the horizontal cylinder, to which the arms b b are secured, and d is the ring or bearing, upon which the said horizontal cyl-

inder *c* is adapted to rotate, the said ring being secured to the shield *C* by means of the brackets *d*' *d*', fixed to its rear end and carrying screws *d*², which engage internally-screwed threaded bearings *d*³, fixed to the shield *C* by means of the supports or legs *d*⁴ *d*⁴.

e is the pulley-ring, which is mounted externally upon the cylinder *c*, the said ring being through the medium of the feather-keys *e*' *e*' secured upon the outside of the cylinder *c* and enabled when rotated to rotate the cylinder *c*, but at the same time to permit the said cylinder to have longitudinal movement relatively with the said pulley-ring.

*e*² is the wire rope or chain, by means of which the pulley-ring *e* is driven, the said wire rope or chain, which is operated from a suitable motor, as hereinafter described, passing over the guide-pulleys *e*³ *e*³, which are rotatably mounted in a bracket *e*⁴, secured to the fixed ring *d*.

f is the annular nut, which is formed upon the inside of the horizontal cylinder *c*, and *f*' is the external screw-thread, formed upon the fast ring or bearing *d*.

With the described arrangement when the pulley *e* is rotated by the wire rope or chain *e*² the cylinder *c* is also rotated through the medium of the feather-keys *e*' *e*' and is simultaneously moved forward by the engagement of the nut *f* with the screw-thread *f*', the pulley *e* being retained in its normal position by the rods *e*⁵ *e*⁵, which are secured at one end to the brackets *e*⁴ and *d*' upon the fixed ring *d* and at the other end engage a flange *e*⁶ upon the pulley-ring *e*, as clearly shown. To reduce friction between the rotating cylinder *c* and the fixed ring *d*, rollers *g* *g* are provided, the said rollers being mounted in bearings on one of the said cylinders.

h *h* are vanes or the like, which are fixed to the face-plate *b* and are adapted to remove the material excavated from the face of the tunnel, the said vanes being arranged at a suitable angle, preferably about thirty degrees to the horizontal, so as to discharge excavated material onto the platform *t* *t*.

Figs. 4 and 5 show suitable driving-gear for operating the wire rope *e*². It comprises a motor *i*, of any suitable kind. In the said figures an electromotor is shown mounted upon a base-plate *i*', supported upon legs or supports *i*², adapted to run upon rails *j* *j*, held upon brackets *j*' *j*', temporarily fixed in the completed portion of the tunnel or heading. The motor-shaft *k* has keyed upon it a worm *k*', which normally gears with a worm-wheel *l* upon a shaft *l*', which carries loosely upon it the wire-rope or chain pulley *m*. This pulley can be rotated by the said shaft *l*' by means of the clutch *m*' when the cutters are to be driven forward at the usual slow speed—that is to say, about two revolutions per minute. When it is required, however, to withdraw the cutters from the head of the excavation, the clutch *m*' is disengaged and

the pulley *m* is driven from the motor-shaft *k* by means of the bevel-wheel *n*, which is fast with the said pulley and which gears with a bevel-wheel *n*', loosely mounted on a stud *n*², supported by the base-plate *i*', the said wheel being rigid with a spur-wheel *n*³, gearing with a pinion *n*⁴, loosely mounted upon the motor-shaft *k*, but being adapted to be rotated thereby through the medium of the clutch *n*⁵ when the clutch *m*' is put out of gear. Means are advantageously provided whereby the two clutches cannot be put into gear simultaneously, either of the two clutches being put into gear while the other is out of gear or both being placed out of gear. A flexible shaft (not shown) is also provided, whereby the motor when both clutches are out of gear can drive the worm *o*, mounted upon the lowermost bracket *d*' of the boring apparatus and which gears with a worm-wheel *o*', keyed upon the lowermost of the screws *d*². Each of the screws *d*² is also provided with a chain-wheel *p*, and the three chain-wheels are geared together by means of the chain *p*', so that when the lowermost screw *d*² is driven by the motor all three of the screws are simultaneously rotated to advance or withdraw the boring apparatus within the shield, as hereinafter described.

The operation of the apparatus is as follows: Assuming the face-plate to be in the position for making a fresh excavation, the motor is started, with the clutch *m*' in gear, so as to drive the pulley-ring *e* at about two revolutions per minute. The rotation of the pulley-ring revolves the face-plate, with its cutters, through the medium of the cylinder *c* and simultaneously advances the said face-plate by reason of the engagement of the nut *f* with the screw-thread *f*' upon the fixed ring *d*. This rotary and forward movement of the cutters excavates the material, which is delivered by the vanes *h* onto the platform *t*, from which it can be loaded into trucks and removed in the usual manner. The forward movement of the cutters being finished, the clutch *m*' is put out of gear and the clutch *n*⁵ put into gear, the motor continuing to rotate, so as to withdraw the cutters into the position shown in Fig. 1 with respect to the fixed ring *d*, the velocity of withdrawal being greater than the speed at which the cutters advance. The clutch *n*⁵ is then also disengaged and the chain-wheels *p* *p* driven by the flexible shaft, so as to rotate the screws *d*², thus withdrawing both the cylinder *c* and the ring *d* within the shield. Piles are then inserted between the front of the shield and the face of the tunnel, and the shield is then forced forward in the usual manner by means of the rams *q*, which may be extended in the usual manner by water compressed by pumps operated from the motor. The peripheral unexcavated portion of the tunnel—that is to say, the portion marked *F*, Fig. 1—is thus cut away by the action of the piles and of the front cutting edge of the shield and the next section of the tun-

nel can be built up in the usual manner. The boring apparatus is then again advanced from the shield and the operation begins *de novo*.

Figs. 6 and 7 show my improvements applied to apparatus where no shield is employed. In this case the ring or bearing *d* is secured to a carriage *u*, which is mounted upon wheels *u' u'*, adapted to run upon rails *u² u²*, laid in the bottom of the finished portion of the tunnel-lining, as clearly shown. To securely hold the boring apparatus in position in the tunnel, lateral arms *v* are provided, the said arms being furnished with slides *v'*, having claws adapted to engage the meeting flanges of adjacent sections of the lining. These claws can be withdrawn to clear the flanges of the tunnel-sections to enable the whole apparatus to be advanced and withdrawn. A shield not being employed in this arrangement, it will be clear that the cutters must excavate the tunnel to the full diameter thereof, as no piles can be used for removing a peripheral uncut portion. The operation of this apparatus is identical with that of the apparatus hereinbefore described, except that the boring apparatus is advanced and withdrawn upon the sliding carriage *u* instead of within the shield.

It will be obvious that in lieu of the elec-
30 tromotor a compressed-air or a hydraulic motor could be used and also that the clutch mechanism shown can be replaced by any other mechanism producing the same results.

Furthermore, as above mentioned the cut-
35 ters may be arranged so as to excavate the whole of the central part of the face of the tunnel instead of leaving a core. I prefer, however, to employ the arrangement shown where a shield is not employed. However, the
40 face-plate cutters preferably cut away to the full diameter of the tunnel or heading, as hereinbefore described, with or without a central uncut core.

Boring apparatus constructed as above de-
45 scribed possesses many advantages, among which may be named the following: By driv-
ing the excavator from a motor independent of and removed from the shield and through the medium of a chain, rope, or belt gear the
50 said motor can work independently of the de-
viations and twisting of the shield to which the excavator is secured and is also inexpen-
sive and simple in construction. By making an annular cut in the manner above described
55 very little ground is left unsupported to slip or move, also economizing mechanical energy and rendering the use of piles with the shield, if one be used, most efficient. The internal friction of the machine is very small, as the
60 main rotating bearings are roller-bearings. The mode of driving described allows of a very flexible connection between the motor and the excavator and between the excavator and the shield, so that breakdowns and dam-
65 ages are reduced to a minimum. Furthermore, the position of the excavator in the

shield allows of full access being obtained thereto for erecting the tunnel-lining and for proceeding with the tunneling or excavation by hand should a breakdown occur. The
70 machine can also be easily and quickly withdrawn to effect repairs and to avoid damage to itself during the advance of the shield, as hereinbefore mentioned.

Having now particularly described and as-
75 ccertained the nature of my said invention and in what manner the same is to be performed, I declare that what I claim is—

1. In apparatus for boring tunnels or head-
ings, the combination with a non-revoluble 80 cylindrical bearing, of a cylinder revolvably mounted upon and surrounding said bearing and capable of moving longitudinally thereof, said cylinder and bearing having the one
85 a nut engaging a screw-thread on the other, means for rotating said cylinder and cutters carried by said cylinder, substantially as de-
scribed.

2. In apparatus for boring tunnels or head-
ings, the combination of a face-plate carry-
90 ing cutters and fixed to a cylinder, of a fixed bearing upon which the cylinder is rotatably mounted and of an internal nut upon the cylinder which engages an external screw-
95 thread upon the fixed bearing for advancing or withdrawing the cylinder relatively with the bearing as the former rotates, substan-
tially as hereinbefore described.

3. In apparatus for boring tunnels or head-
ings, the combination with a non-revoluble 100 hollow cylindrical bearing of a cylinder mounted revolvably upon and surrounding said bearing and being capable of sliding lon-
gitudinally thereof said cylinder and bearing having the one a nut engaging a screw-thread 105 on the other, means for rotating said cylin-
der and an annular series of cutters secured to said cylinder, whereby a central uncut por-
tion or core is left in the tunnel which will project into said cylinder and bearing, sub-
stantially as described.

4. In apparatus for boring tunnels or head-
ings, the combination with a non-revoluble hollow cylindrical bearing of a cylinder mounted revolvably upon and surrounding 115 said bearing and being capable of sliding lon-
gitudinally thereof said cylinder and bearing having the one a nut engaging a screw-thread on the other, means for rotating said cylin-
der, an annular face-plate secured to said cyl- 120 inder, a series of cutters carried by said face-
plate, and means for moving said bearing longitudinally, substantially as described.

5. In apparatus for boring tunnels or head-
ings the combination of a face-plate carrying 125 cutters, of a cylinder to which the face-plate is secured and of a fixed bearing upon which the said cylinder rotates, of an external pul-
ley-ring upon the cylinder with which en-
gages a rope, chain or belt driven from a suit-
able motor and of an internal nut upon the cylinder which gears with an external screw-

thread upon the fixed bearing, substantially as hereinbefore described.

6. In apparatus for boring tunnels or headings the combination of cutters secured to a cylinder rotatably mounted upon a bearing and of means for advancing and withdrawing the bearing and cylinder, substantially as, and for the purpose, hereinbefore described.

10 7. In apparatus for boring tunnels or headings the combination of a face-plate carrying cutters, of a cylinder to which the said face-plate is fixed, of a fixed bearing upon which the cylinder is rotatably mounted, of means

15 for rotating the cylinder, of screws fixed to the bearing and mounted in nuts upon supports fixed in the shield, tunnel or excavation and of means, such as worm-gear, for

rotating the screws, substantially as, and for the purpose, described.

8. In apparatus for boring tunnels or headings, the combination with a cylindrical bearing, of a cylinder mounted on and surrounding said bearing, and capable of movement longitudinally thereof, said bearing and cylinder being provided the one with a nut engaging a screw-thread on the other, cutters secured to said cylinder, means for rotating said cylinder, and mechanism connected with said bearing for moving it longitudinally, substantially as described.

ARTHUR WOODROFFE MANTON.
